CIRCUIT BREAKER

Joseph A. Drobney, Duquesne, and Paul W. Brown, Beaver Falls, Pa., assignors to Westinghouse Electric Corporation, East Pittsburgh, Pa., a corporation of Pennsylvania

Application February 7, 1952, Serial No. 270,401

11 Claims. (Cl. 200—88)

1

This invention relates to circuit breakers and more particularly to circuit breakers for controlling lighting and moderate power circuits.

An object of the invention is to provide a circuit breaker embodying a bimetallic switch member operative to effect automatic opening of the breaker and having spring means biasing the switch member closed in the closed position of the breaker and which also biases the switch member open in the open position of the breaker.

Another object of the invention is to provide a circuit breaker that is trip free of the manual operating means wherein a thermally responsive element constitutes both the movable contact carrying means and the trip means and cooperates with an overcenter spring to form the automatic opening means.

Another object of the invention is to provide a circuit breaker having a minimum number of parts, of rugged construction and reliable in operation and inexpensive to manufacture.

The novel features that are considered characteristic of the invention are set forth in the appended claims. The invention itself, however, both as to structure and operation, together with additional objects and advantages thereof will be best understood from the following detailed description when read in conjunction with the accompanying drawing.

In said drawing:

Figure 1 is a side elevational view partly in section with the cover plate substantially broken away of a circuit breaker embodying the principles of the invention, the breaker being shown in the closed position.

Fig. 2 is a side elevational view similar to Fig. 1 but showing the breaker in the automatically opened position.

Fig. 3 is a horizontal sectional view taken along line III—III of Fig. 1.

Fig. 4 is a vertical sectional view taken along line IV—IV of Fig. 1.

Fig. 5 is a horizontal sectional view taken substantially along line V—V of Fig. 1.

Fig. 6 is a perspective view showing a part of the operating mechanism.

Referring to Fig. 1 of the drawing, the circuit breaker comprises an enclosing housing 11 and a cover plate 13 (a fragment only of which is shown) both made of insulating material, a stationary contact 15, a movable contact 17 and an operating handle 19. The stationary contact 15 is mounted on the inner end of a conducting strip 21 which is laid into an opening in the housing 11 and has a terminal connecting means 23 at the

2

outer end thereof. The movable contact 17 is carried on the end of a thermally responsive movable switch member 25 which is composed of a strip of bimetallic material. The bimetallic switch member 25 is welded or otherwise suitably secured to a pivot pin 27 mounted for rotation in companion openings in the side wall of the housing 11 and the cover 13.

The bimetallic switch member 25 adjacent the end thereof opposite to the contact 17 is provided with a shouldered portion 29 on which is mounted an angular operating member 31 pressed against the shoulders by means of an overcenter spring 33. In the closed position of the breaker, the overcenter spring 33 together with the portion of the bimetallic switch member 25 to the left of the pivot pin 27 forms a toggle having its knee joint at 29 by which the spring 33 biases the contact 15—17 closed and provides contact pressure.

A flexible conductor 34 connects the bimetallic switch member 25 at a point adjacent the left hand end thereof to the inner end of a conducting strip 36 which at its outer end carries a terminal connector 38.

The operating handle 19 is pivotally mounted on pivot projections 35 supported in the side wall of the housing 11 and the cover 13. The handle 19 extends outwardly through an opening 37 in the housing, which opening is substantially closed in all positions of the handle by a circular portion 39 of the handle 19. A spring 41 having one end hooked over a pin 43 extending between two bifurcated portions of the handle 19 and the other end attached to the bimetallic switch member 25 at a point to the left of the pivot pin 27 biases the handle 19 to the "on" position and biases the bimetallic switch member 25 in a clockwise or opening direction about the pivot 27.

With the handle 19 in the "on" position, however, the spring 41 has insufficient force to overcome the spring 33 and move the switch member to the open position. When the handle 19 is moved as far as it will go in a clockwise direction to the "off" position, the tension of the spring 41 is increased to the point where it overcomes the force of the overcenter spring 33 and moves the toggle 23—25 overcenter and moves the bimetallic switch member 25 to the open position with a snap action. A shoulder 44 on the housing 11 acts as a stop to limit the opening movement of the switch member.

When the handle 19 is moved to the "off" position spaced projections 45 on the inner end thereof are moved to a position above the ends 32

of the actuating member 31 as shown in dot and dash lines at 45a in Fig. 2. When the handle 19 is moved counterclockwise to the "on" position the projections 45 engage the spaced ends 32 of actuating member 31 and moves the toggle 33-25 overcenter in closing direction. As soon as the toggle is moved overcenter the spring 33 acts to move the switch member 25 to the closed position to close the contacts with a snap action.

The circuit breaker is opened automatically in response to low overload currents of, for instance, up to ten times normal rated current by the bimetallic switch member 25. The high expansion side of the bimetal 25 is on the lower side, consequently, as the bimetal becomes heated by the flow of overload current the ends of the bimetal tend to move upwardly. Since the contact end of the bimetal switch member cannot move upwardly and since the bimetal is mounted on the pivot 27 the distortion of the bimetal will cause a slight clockwise rotation of the bimetal element about the pivot 27 and at the same time cause upward movement of the left end thereof. This action will compress the spring 33 and cause upward overcenter movement of the toggle 33-25, whereupon the spring 33 will move the switch member 25 to the open position to open the contacts with a snap action.

When the bimetallic switch member 25 moves to the open position during an automatic opening operation, the tension of the spring 41 is reduced to a point where a spring 47, compressed between a spring seat in the housing 11 and the handle 19, partially overcomes the tension of the spring 41 and moves the handle to a trip indicating position as shown in Fig. 2.

With the parts in the tripped-open position as shown in full lines in Fig. 2, it is necessary, before the contacts can be closed, to engage the projections 45 back of the actuating member 31. This is accomplished by moving the handle 19 clockwise to the "off" position. During this movement the projections 45 wipe by the spaced ends 32 of the actuating member 31 which is then snapped back to the position in which it appears in Fig. 2 by the spring 33. The breaker may then be closed in the previously described manner by counter-clockwise movement of the handle to the "on" position.

The circuit breaker is opened instantaneously in response to overload currents of ten times or more of the normal rated current or in response to short circuit currents by means of an electromagnet 49 comprising a fixed magnet yoke 51 supported in recesses between the side wall of the housing 11 and the cover 13 and an armature 53 secured to the bimetallic switch member 25 to the left of the pivot 27.

Upon the occurrence of an overload current of ten times or more of normal rated current or a short circuit current the electromagnet 49 is energized by the current flowing through the bimetallic switch member, and attracts the armature 53 which causes instantaneous movement of the switch member 25 to the open position. This action also causes the toggle 33-25 to move overcenter in an upward direction to the position shown in Fig. 2 where the spring 33 biases the switch member 25 to the open position, and the spring 47 moves the handle 19 to the trip indicating position. The breaker is then closed in the previously described manner by first moving the handle 19 to the "off" position in order to position the projections 45 back of the ends 32 of the actuator 31 as shown in

dot and dash lines in Fig. 2. The contacts are then closed by counter-clockwise movement of the handle 19 to the "on" position during which movement the projections 45 move the actuator 31 and thereby the toggle 33-25 overcenter in a downward direction and closes the contacts with a snap action.

The circuit breaker is trip-free of the handle. That is, the breaker will automatically trip open in response to overload circuits even if the handle is held in the closed position. The circuit breaker is of simple construction comprising a minimum number of parts that are inexpensive to manufacture, and are easily assembled and calibrated since all of the parts are held in assembled relation by being received by recesses and projections on the base and cover of insulating material. The switch member which is constructed of bimetallic material constitutes the contact carrying means and the tripping means and also, together with the overcenter spring, comprises the means for automatically opening the contacts.

While the invention has been disclosed in accordance with the provisions of the patent statutes, it is to be understood that various changes in the structural details and arrangement of parts thereof may be made without departing from some of the essential features of the invention.

We claim as our invention:

1. A circuit breaker comprising stationary and movable contacts, a thermally responsive switch member mounting said movable contact on one end thereof for movement into and out of engagement with said stationary contact, an overcenter spring cooperating with the other end of said thermally responsive switch member normally biasing said switch member to closed position, thermal bending of said switch member moving said overcenter spring to an overcenter position wherein said overcenter spring moves said switch member to open position to open said contacts with a snap action, a manual operating member movable to an open and to a closed position, and a joint between said overcenter spring and said thermally responsive switch member operable by said manual member to move said overcenter spring to another overcenter position wherein said spring moves said thermally responsive switch member to closed position to close said contacts with a snap action.

2. A circuit breaker comprising stationary and movable contacts, a thermally responsive switch member mounting said movable contact at one end thereof for movement into and out of engagement with said stationary contact, said thermally responsive switch member being connected to be traversed by the current of the circuit, spring means cooperating with the other end of said switch member normally biasing said thermally responsive switch member to closed position, means supporting said thermally responsive switch member at a point between its ends, thermal bending of said switch member moving said spring means to a position wherein said spring means acts to move said switch member about said support means to an open position to effect opening of said contacts with a snap action.

3. A circuit breaker comprising stationary and movable contacts, a thermally responsive switch member mounting said movable contact at one end thereof for movement into and out of engagement with said stationary contact, said thermally responsive switch member being connected

to be traversed by the current of the circuit, spring means cooperating with the other end of said thermally responsive switch member normally biasing said thermally responsive switch member to closed position, means supporting said thermally responsive switch member at a point between its ends, thermal bending of said thermally responsive switch member moving said spring means to a position wherein said spring means acts to move said switch member about said support means to an open position to effect opening of said contacts with a snap action, an actuating member disposed between said spring means and said switch member, and manually operable means for engaging said actuating member and moving said spring means to a position where said spring means moves said switch member to effect closing of said contact with a snap action.

4. A circuit breaker comprising stationary and movable contacts, a thermally responsive switch member comprising a bimetallic member mounting said movable contact on one end thereof for movement into and out of engagement with said stationary contact, means supporting said bimetallic switch member at a point between its ends, spring means cooperating with the other end of said switch member to form a toggle having a normal overcenter position in which said spring means biases said bimetallic switch member closed, said toggle being movable to a second overcenter position in which said spring means biases said switch member open, thermal bending of said bimetallic switch member moving said toggle to said second overcenter position to effect opening movement of said bimetallic switch member and opening of said contacts.

5. A circuit breaker comprising stationary and movable contacts, a thermally responsive switch member comprising a bimetallic member mounting said movable contact on one end thereof for movement into and out of engagement with said stationary contact, means supporting said bimetallic switch member at a point between its ends, spring means cooperating with the other end of said switch member to form a toggle having a normal overcenter position in which said spring means biases said switch member closed, said toggle being movable to a second overcenter position in which said spring means biases said switch member open, thermal bending of said bimetallic switch member moving said toggle to said second overcenter position to effect opening movement of said switch member and opening of said contacts, and manual means for engaging and moving said toggle to said normal overcenter position to effect closing movement of said bimetallic switch member and closing of said contacts.

6. A circuit breaker comprising stationary and movable contacts, a bimetallic switch member mounting said movable contact at one end thereof for movement into and out of engagement with said stationary contact, pivot means pivotally supporting said bimetallic switch member at a point between its ends, an overcenter spring cooperating with the other end of said bimetallic switch member to form a toggle, said toggle having a first overcenter position in which said overcenter spring biases said bimetallic switch member closed and a second overcenter position in which said overcenter spring biases said bimetallic switch member open, manual operating means including an operating handle movable to an "on" and to an "off" position, a spring means

connected under tension between said handle and said toggle, said handle when moved to said "off" position increasing the tension of said spring means to cause movement of said toggle to said 5 second overcenter position and opening movement of said bimetallic switch member, and means on said handle operable when said handle is moved to said "on" position to engage and positively move said toggle to said first overcenter position to effect closing movement of said bimetallic switch member.

7. A circuit breaker comprising stationary and movable contacts, a bimetallic switch member mounting said movable contact at one end thereof for movement into and out of engagement with said stationary contact, pivot means pivotally supporting said bimetallic switch member at a point between its ends, an overcenter spring cooperating with the other end of said bimetallic switch member to form a toggle, said toggle having a first overcenter position in which said overcenter spring biases said bimetallic switch member closed and a second overcenter position in which said overcenter spring biases said bimetallic switch member open, manual operating means including an operating handle movable to an "on" and to an "off" position, a spring means connected under tension between said handle and said toggle, said handle when moved to said "off" position increasing the tension of said spring means to cause movement of said toggle to said second overcenter position and opening movement of said bimetallic switch member, and means on said handle operable when said handle is moved to said "on" position to engage and positively move said toggle to said first overcenter position to effect closing movement of said bimetallic switch member and thermal bending of said bimetallic switch member causing movement of said toggle to said second overcenter position to effect automatic opening movement of said switch member.

8. A circuit breaker comprising a bimetallic switch member movable to open and close said circuit, said bimetallic switch member being disposed to be heated by the current of the circuit, means supporting said bimetallic switch member at a point between the ends thereof, spring means cooperating with one end of said bimetallic switch member to form a toggle, said toggle having a normal position in which said spring means biases said bimetallic switch member closed and movable to a second position in which said spring means biases said bimetallic switch member open, thermal bending of said bimetallic switch when heated a predetermined amount in response to overload currents below a predetermined value moving said toggle to said second position to effect opening movement of said bimetallic switch member, electroresponsive means operable in response to overload currents above said predetermined value to move said toggle to said second position to effect instantaneous opening movement of said bimetallic switch member, and manual means movable to an "off" and to an "on" position operable to engage and positively move said toggle to said normal position to move said bimetallic switch member to the closed position.

9. A circuit breaker comprising a housing, a switch member comprising a straight strip of bimetallic material movable to open and close said circuit, pivot means pivotally supporting said bimetallic switch member at a point between the ends thereof, a compression spring compressed 75 between said housing and one end of said bime-

tallic switch member and forming a toggle with said switch member, said toggle having a first position in which said compression spring biases said bimetallic switch member closed and a second position in which said spring member biases said bimetallic switch member open, manual operating means comprising a handle movable to an "off" and to an "on" position, a spring connected under an initial tension between said handle and said toggle, movement of said handle to said "off" position increasing the tension of said spring to cause overcenter movement of said toggle to said second position to effect opening movement of said switch member, and said bimetallic switch member when heated by overload currents bending in a direction to cause movement of said toggle to said second position to effect automatic opening movement of said switch member.

10. A circuit breaker comprising a housing, a switch member comprising a straight strip of bimetallic material movable to open and close said circuit, a pivot means pivotally supporting said bimetallic switch member at a point between the ends thereof, a compression spring compressed between said housing and one end of said bimetallic switch member and forming a toggle with said switch member, said toggle having a first position in which said compression spring biases said bimetallic switch member closed and a second position in which said spring member biases said bimetallic switch member open, manual operating means comprising a handle movable to an "off" and to an "on" position, a spring connected under an initial tension between said handle and said toggle, movement of said handle to said "off" position increasing the tension of said spring to cause overcenter movement of said toggle to said second position to effect opening movement of said bimetallic switch member, and said bimetallic switch member when heated by overload currents bending in a direction to cause movement of said toggle to said second position to effect automatic opening movement of said bimetallic switch member and a projection on said handle operable when said handle is moved to said "on" position to engage and move said toggle to said first position to effect closing movement of said switch member.

11. A circuit breaker comprising stationary and movable contacts, a bimetallic switch member mounting said movable contact on one end thereof for movement into and out of engagement with said stationary contact, pivot means pivotally supporting said bimetallic switch member at a point between the ends thereof, an overcenter spring cooperating with one end of said bimetallic switch member to form a toggle, said toggle having a first overcenter position in which said overcenter spring biases said bimetallic switch member closed and being movable to a second overcenter position in which said overcenter spring biases said switch member open, manual means movable to an "on," an "off" and to a "trip indicating" position, a tension spring connected with an initial tension between said handle and said toggle, said handle when moved to said "off" position increasing the tension of said tension spring to cause movement of said toggle to said second overcenter position to effect opening movement of said bimetallic switch member, means on said handle operable when said handle is moved to said "on" position to engage and move said toggle back to said first overcenter position to effect closing movement of said bimetallic switch member, thermal bending of said bimetallic switch member causing automatic movement of said toggle to said second overcenter position to effect automatic opening movement of said bimetallic switch member, a compression spring biasing said handle to said "trip indicating" position, and automatic movement of said toggle to said second overcenter position decreasing the tension of said tension spring to permit said compression spring to move said handle to said "trip indicating" position.
